11 Claims. (Cl. 197—49)

Our invention relates to typewriters and re-
lates more particularly to typewriters adapted to
be used in a telegraph typewriter system of the
general type wherein a message transmitted from
5 a station may be automatically received at a dis-
tant station and reproduced in printed characters
thereat.

An object of our invention is to provide a type-
writer for the transmission of such message
10 which may be operated under the control of a
keyboard such as is commonly used for ordinary
typewriters, whereby no special training is re-
quired for its operation.

Another object of our invention is to provide a
15 typewriter to be used in a telegraphic system
which will not be substantially affected by the
variation of voltage and frequency allowable in
commercial electrical power plants nor be sub-
ject to a reduction in accuracy or efficiency there-
by.

20 Another object of our invention is to accom-
plish the continuous feeding of paper to the
printing mechanism and to permit the loading
of both sending and receiving machines with
25 sufficient paper for a considerable period of
operation.

Another object of our invention is to accom-
plish a satisfactory speed of message transmis-
sion and reception, with a minimum of wear on
30 the typewriter.

Another object of our invention is to operate
ribbon feed and reverse by a rack on a paper
carriage, and only in the spacing direction of
movement of the carriage.

35 Another object of our invention is to first raise
a ribbon elevator by a printing hammer and then
raise the printing hammer by the stoppage of
the ribbon elevator.

Another object of our invention is to provide
40 a printing hammer in combination with a ribbon
elevator whereby hammer action follows the
movement of the ribbon elevator with a quick
blow.

45 Another object of our invention is to provide a
ribbon elevator in combination with a printing
hammer, and a magnet and thus to accomplish
several operations by a single tractive effort of
the magnet.

50 Another object of our invention is to accom-
plish the bridging of a paper carriage and paper
roll by a printing hammer and ribbon elevator
mechanism.

Another object of our invention is to provide
55 a traction system for a paper carriage having

self-cleaning, self-aligning, and anti-friction
truck and rails for the paper carriage.

Another object of our invention is to provide
a paper shift in combination with a carriage
return. 5

Another object of our invention is to provide
an automatic releasing and locking (in two posi-
tions) clutching element.

Another object of our invention is to provide
a clutching mechanism which after being tripped 10
completes its cycle of operation automatically.

Another object of our invention is to provide
a compensating carriage retriever and paper
supply carried by the carriage.

Another object of our invention is to provide 15
relative positioning of a roll of paper, paper feed
rolls, and guides, whereby the "curl" of the
printed sheet is such as to cause the sheet, upon
exit from the machine, to turn backward in-
stead of forward.

Another object of our invention is to provide 20
paper feed movements free for manual rotation
in both directions when placing new paper supply
in a carriage.

Another object of our invention is to provide 25
a printing mechanism whereby the sequence of
operation in the ribbon shift and hammer move-
ment is always in the proper relation.

Another object of our invention is to provide
a combined paper feed and carriage return mech- 30
anism whereby the paper feed is effected regard-
less of whether any carriage movement takes
place or not.

Another object of our invention is to provide
a paper roll, a paper carriage, and feed mech- 35
anism in combination whereby the paper is al-
ways in alignment with the paper guides and no
mutilation of the edges of the paper will occur.

Other objects of our invention and the inven-
tion itself will become apparent from the follow- 40
ing description of an embodiment of our inven-
tion, and in which description reference will be
had to the accompanying drawings, illustrating,
mostly diagrammatically, the said embodiment.

45 Referring to the drawings:
Fig. 1 shows in schematic view the controlling
apparatus for positioning the typewheel for print-
ing operations in an embodiment of our inven-
tion;

Fig. 2 shows, mostly in section, a slipping 50
clutch through which motion is communicated
to apparatus of the embodiment of our invention
herein illustrated and described;

Fig. 3 shows in isometric view a transmitter
operator mechanism; 55

Fig. 4 is a view partly in section, showing the arrangement of portions of the apparatus of the transmitting mechanism of Fig. 3;

Fig. 5 is a schematic view of printing mechanism adapted for use in the said embodiment of our invention;

Fig. 5a is a view of some of the apparatus of Fig. 5 in side elevation;

Fig. 6 is a schematic view of paper carriage controlling mechanism adapted to be employed in the said embodiment;

Fig. 6a is a side elevational view of a paper carriage and associated mechanism adapted to be employed in the said embodiment;

Fig. 7 is a view of controlling mechanism comprising a motor circuit switching means adaptable for use in apparatus of the said embodiment;

Fig. 7a is an end view of some of the apparatus illustrated in Fig. 7;

Fig. 10 is a diagram chart relating to character type selection;

And Figs. 11 and 12 are views of a contact finger and ratchet wheel, respectively, illustrated in Fig. 3.

In the above different figures of drawings, the same parts are designated by like reference characters.

In the following description of apparatus of the present application, such description will be had, in connection with a telegraph typewriter system, in which the present invention may be advantageously employed, and which system is more particularly described and claimed in our co-pending application for United States Letters Patent, Serial No. 134,882, filed September 11, 1926, for Telegraphic typewriter systems and apparatus therefor.

Generally, such a telegraph typewriter system consists of a printing telegraph system comprising two or more printing telegraph machines; line circuits interconnecting the machines; each machine comprising an operating motor, a receiving mechanism and a transmitting mechanism, and transmitting and receiving mechanisms, a "start" and a "break" typewriter key at each machine, and an electric switch operable by the "start" key adapted, when depressed, to effect the transmission of current over the line circuits to the distant machines and to effect the starting of the motors of all the machines in the circuit, means at each machine responsive to the starting of its motor adapted to effect continuous operation thereof independently of the position of said switch, the "break" key when operated adapted to disassociate the transmitting circuits from the line circuits and to associate the receiving circuits therewith, and discontinue the transmission of current to the distant machine over the line circuits.

It is also well to note, moreover, that operation of the receiving station is controlled through the use of an impulse system of short and long impulses, which makes it possible to transmit 75 and select a comparatively large number of

characters with few impulses and with a reasonably simple machine. Preferably, the transmission of the character impulses is accomplished with a standard typewriter keyboard, described herein, more fully described in our co-pending application for United States Letters Patent, Serial No. 134,882, filed September 11, 1926, for Telegraphic typewriter systems and apparatus therefor, hereinbefore referred to, though other types of transmitting apparatus may be employed. 10

Referring to Fig. 1 of our drawings at 71 we show a typewheel, upon which the printing type characters appear, having, in the embodiment illustrated, three rows of characters around its periphery, the three rows being herein arbitrarily called channels 1, 2 and 3 (left to right) and, each row of three characters across the face of the wheel is herein arbitrarily called a division. The wheel is loosely mounted, but is keyed to the rotatable driven shaft 72 in such a manner that the wheel will rotate with the shaft at all times, but it can also be shifted longitudinally of the shaft at any time. The wheel has, in addition to the hole in its hub for the shaft 72, two separate holes near its rim through which two pins 14 protrude, and which pins are carried by a yoke 73, which is rigidly secured to the shaft 72. As the shaft 72 is rotated the yoke and pins 14 will cause the typewheel to be rotated also, and at the same time, the wheel may be axially shifted 20 longitudinally on the shaft and pins. This arrangement makes it possible to bring any one of the several printing type characters on the typewheel 71 to a position in alignment with the path of the printing hammer, later to be described. 25 The selection of the individual characters in any one channel is accomplished by the operation of an escapement unit which will now be described.

Three escape wheels 75, 76 and 77 are preferably closely positioned together and associated as one unit in practice, but, in the drawings, these are shown separately, in order to better explain and illustrate the essentials and mode of operation of the unit. Escape wheel 75 has a definite number of teeth, the amount depending upon the largest number of divisions provided in any of the channels; one tooth is provided for each of the divisions thereof. Additional teeth may be provided for various purposes. Escape wheel 76 is preferably of the same general design, except that it has fewer suitably spaced teeth. Escape wheel 77 is also preferably of the same type with the exception that it has but one tooth. The number and disposition of the teeth on the different wheels that make up the escapement unit 55 are varied for reasons which will be apparent from the following description.

This set of escape wheels is rigidly mounted on shaft 72 and rotates therewith. Operating in conjunction with, and, controlling the movement of the escape wheels is a set of two finger units, comprising pawls, 78 and 79, each finger unit being composed of a finger and a grooved sleeve 106 capable of sliding on a shaft 80. Shaft 80 is pivoted at each end so as to oscillate 65 to the limit of the finger movement on the escape wheels. Fixed to the center of shaft 80 is a hub 81, to which is connected a link through which the oscillations are transmitted to the shaft. The hub also carries a pin 86 which passes loosely 70 through a hole in each of the two fingers and which communicates the oscillatory movements from the hub 81 to the fingers and at the same time permitting the fingers to move freely longitudinally of the shaft. The oscillatory, or rotary 75

motion of the shaft 80 and fingers 78 and 79, is communicated through the link extending from the armature 85 of magnet 87. The armature 85 is pivoted on a pin 90 spaced therefrom 5 toward the observer and spring 91 spaced from the pin toward the observer normally retracts it from magnet 87 and also keeps finger 78 in engagement with escape wheel 75 through the link connection. The horizontal motion of the 10 fingers 78 and 79 is controlled by the magnets 89 and 88 through armatures 83 and 84. In their normal position the fingers 78 and 79 are in alignment with escape wheel 75, the finger 78 engaging same at the top. Should magnet 88 15 be energized, its armature 84 being engaged in the slot in the hub of finger 79 will cause the finger to move to the left along shaft 80 and align it with escape wheel 76. This same operation also takes place with magnet 89, armature 20 83 and finger 78, this finger aligning with escape wheel 77 when moved along the shaft 80 to the right.

When magnet 87 is energized, armature 85 through its link connection to shaft 80 will cause 25 finger 78 to move upward and free of the tooth of escape wheel 75 and bring finger 79 upward into engagement with another tooth of the escape wheel 75.

The shaft 72 carries at its right hand end, 30 one clutch element of a friction clutch 82, the second clutch element associated with the element 82 (see Fig. 2, to be described) being driven by an electric motor while the machine is operating. The shaft 72 is adapted to be 35 driven through the friction clutch 82 by a motor driven shaft 92. During such periods wherein current is not applied to the magnet 87, the finger 78 holds the shaft 72 stationary, by virtue 40 of the slipping occurring between the two elements of the friction clutch 82. Owing to the frictional drag of the clutch unit, there is applied to the shaft 72 a steady torque which causes 45 rotation of this shaft at all such times when it is released by the escapement unit.

If now, energy is applied to magnet 87, fingers 78 and 79 will be raised, allowing the escapement unit and typewheel to advance one-half division, as finger 78 will release the tooth with which 50 it is engaged and, finger 79 will engage with the approaching tooth on the under side of the escape wheel. When the magnet 87 is de-energized, the operation of the fingers will be reversed and the shaft and wheels will advance 55 another half division. Each cycle as explained, will advance the typewheel one division, and, if a series of impulses is applied to the magnet 87 the typewheel will be advanced to some predetermined division, depending upon the number 60 of impulses in the series.

As can be understood at this time, if all the escape wheels were divided into a great many divisions, it would require a long series of impulses to rotate the typewheel to the desired 65 characters. This would require a comparably longer time for transmission so in order materially to reduce the number of impulses required for a definite number of characters and, consequently, to considerably reduce the time required 70 for telegraphic transmission thereof, the escape wheel 76 is brought into operation through the shifting of finger 79, resulting from a movement of the armature 84, into alignment with escape wheel 76. Armatures 85 and 83 so differ from 75 armature 84 in weight and other factors affect-

ing their inertia and the forces effective upon them are so proportional that they differ in their rates of responsiveness to the operative magnetic forces exerted upon them characteristics to cause armatures 85 and 83 to respond very 5 quickly whereby they will be actuated by both short and long impulses of current passed through their electro-magnets and armature 84 is relatively sluggish and responds only to longer continued impulses of current. From the foregoing, it is obvious that, if current is applied to magnets 87 and 88, at the same time, if only for a sufficiently short period of time, only armature 85 will operate and the typewheel will be stepped around accordingly, as before described; 10 however, should a longer impulse be simultaneously applied to both magnets, both armatures 85 and 84 will be operated.

As before stated, upon each operation of the armature 85, the typewheel 71 will be rotatively 20 advanced one division, and if the impulse should be a long one whereby armature 84 is also operated, finger 79 will be shifted over in alignment with escape wheel 76; if now the finger 79 comes into engagement with such a tooth on wheel 76, 25 as may be disposed one division further around the wheel than the normal position of the finger, the typewheel will then be advanced but one division; however, should finger 79 be brought into relation with escape wheel 76 at a point where 30 the approaching teeth in its rotation have been receded, the result of the longer impulse will be to allow the typewheel to travel a greater distance, or, several divisions depending upon the number of teeth omitted on the wheel in the distance moved. The typewheel can, therefore, be advanced to selected position much faster with fewer impulses than would be otherwise possible. It has been above stated that if finger 79 comes 35 into alignment with a tooth on escape wheel 76 40 which follows the tooth in normal relation with the finger 79, the typewheel will be advanced but one division. Now, this condition holds good for the first two divisions that the typewheel is advanced by any series of impulses; the typewheel 45 is never advanced more than one division for each of the first two impulses, whether they be long or short, due to the fact that there are two teeth provided on wheel 76 that engage with the finger 79 on the first two divisions, if the impulses received while the finger is aligned with wheel 76 50 are of the longer continued character.

This makes it possible to utilize the movement of armature 84 on the first two impulses for the shifting of the typewheel from its normal 55 position in channel 1, to either of the channels 2 or 3.

The shift and control of the typewheel is accomplished as follows:—Typewheel 71 is held in its normal position by arm 93 secured to the armature 94 of magnet 104 engaging within a slot in the typewheel hub 50 and, as shown, is pivoted at its lower end. Any movement of arm 93 to the left, will cause typewheel 71 to be moved along the shaft 72 in the same direction and for the same distance. The movement of wheel 71 through arm 93 is controlled by an escapement arm 95 and a pin 96. The arm 95 is pivoted at its extreme right end 48, which also carries a right angle slotted extension 49. It can be seen, 70 that, if an impulse is imparted to the slotted extension, in line with the slot 47, and, in a left-hand direction, the first tooth 46 in the escapement which engages pin 96 will be lifted clear of the pin, and the arm 93 will move to the left 75

until pin 96 engages the single tooth 45 on the lower side of the arm. Following the impulse, the arm will drop back to its normal position, allowing the pin to shift from the lower to the 5 second of the upper teeth 44 of the escapement. This permits an axial movement of the type-wheel moved by the spring 97 an amount equal to the width of one channel and aligns the second channel with the printing hammer not herein 10 shown but adapted to be reciprocated in a plane at right angles to the axis of the shaft 72 to compress interposed layers of typewriter printing ribbon and a sheet of paper upon which the typewritten record is to be made against the 15 type raised characters on the typewheel 71 as hereinafter more specifically described. A second impulse to the arm 95 will cause the wheel to be shifted to the third channel in the same manner as to the second, the impulses mentioned, 20 being communicated to the arm 95 by movement of armature 84, which in turn operates responsive to long impulses of current through electromagnet 88.

By virtue of the axial positioning of the type-wheel, controlled by the first two impulses in magnet 88 and due to the fact that its armature 84 only operates responsive to the longer impulses, the typewheel may be shifted to any desired channel by the transmission of the first two impulses 25 of any series in a combination of long and short impulses. For example, although two short impulses will not effect the armature 84 to shift the wheel, one short and one long impulse will shift it to the second channel; two long impulses will 30 shift the wheel to the third channel since the long impulses are effective to operate armature 84, which controls the actuation of escapement 95.

Contact between attracted armature 84 and escapement arm 95 would cause the typewheel to shift from the first to the second or third channel; so it is desirable that this should not happen on any but the first two impulses in any one series since, otherwise, the desired selection would 40 not be accomplished. To prevent such undesired operation, control over the escapement 95 is exercised by a cam 98 on the shaft 72 adapted to actuate a baffle plate element, comprising a sleeve 100 to one end of which is fixed an arm 101 operated by cam 98, and to the other end a flexible thin metallic guard or baffle plate 102 is secured. This unit is free to turn on the shaft 103. When the arm 101 is, once during each rotation of the shaft 72, raised by the cam 98, the flexible guard 45 or baffle plate is disposed directly between the projection 99 on armature 84 and a bifurcated end of the arm 95. The cam holds the baffle plate in this position while wheel shaft 72 rotates two divisions from normal. Just before the third division 50 is reached in the rotation of the shaft 72 the cam 98 releases the arm 101 and the baffle plate swings clear of, and out of alignment with the bifurcated arm of escapement 95 and armature 84. In this position the armature has no effect upon the escapement 95 due to the projection 99 on the armature passing freely between the forks of the end of the escapement lever arm and the typewheel will remain in the 55 position previously achieved through the influence of the first or second impulses of a particular series.

The typewheel is restorable to its normal position by the attraction of magnet 104 on the armature end of the arm 93. The armature 84 60 operates the typewheel shifting mechanism and

armature 83 operates the paper carriage shift by actuating the paper carriage escapement pawl 41; a projection on armature 83 is adapted to activate the escapement pawl 41 directly and at any time the armature 83 is moved. The carriage escapement is described elsewhere herein and may vary in construction, the usual typewriter spring-propelled carriage being suitable for the purpose.

The armature 83 engages the groove in the 10 sleeve 106 of finger 78 and when magnet 89 is energized, its armature 83 will shift the finger 78 to the right and in alignment with escape wheel 77 which has but one tooth.

This operation permits the shaft 72 with all 15 its associated units to return to normal position, after the second division in the revolution is reached. The single tooth 77A is in alignment with the normal position of the finger 78 on the escape wheel 75 and after one or more divisions 20 have been traversed by the units on the shaft 72 and the finger 78 shifted to escape wheel 77, the shaft and associated units will continue to rotate for the remainder of one revolution after which the finger engages the single tooth 77A 25 at which time the mechanism will again be in normal position. This restoring takes place after the selection and printing of each character, as the shaft 72 and typewheel 71 complete one revolution of each cycle of operation. 30

Cams 107, 108 and 109 operate contact combinations 110 and 111 and 112 at times predetermined by the radial disposition of the cams on the shaft, during each revolution of the shaft 72. Cam 109 operates contacts 112 indirectly 35 through the movement of armature 113. When shaft 72 is in its normal position, cam 109 is in engagement with armature 113 and holds same in an operated position in relation to the magnet 114 and keeps contacts 112 open. The relation 40 and functioning of this combination will be explained later.

Springs such as 91, 97, 115, 116, 117 and 118, are provided for the return operation of the armatures and all moving parts. 119 represents 45 bearings for shaft 72. It will be understood that suitable adjustable stops of well known types, but not shown herein may be also provided to limit the movement of the several oscillating members.

The friction clutch 82 is a part of the selector unit and the clutch element thereof attached to the shaft 72 is shown (Fig. 2) as a hollow chamber or drum supported from one end by a sleeve encircling shaft 72. The clutch element thereof 50 fastened to the drive shaft is shown as a block through which is cut a hole at a right angle to the shaft. Riding free within each end of this hole, is a thin sleeve into which is placed a friction pad of preferably fibrous material, such as 60 felt which acts to frictionally engage the drum to rotate same when the clutch unit is assembled and operated. This block rotates within the drum and two springs pressing against the under side of the sleeves force the friction pads against 65 the inner surface of the drum. With a tapered sleeve as shown on shaft 92 the springs can be adjusted to the right tension and a very smooth and positive operation of the clutch obtained.

The secured typewheel shift member 93 also operates the contact group 440, the right hand contacts being closed when the wheel is set in the first channel, and, the left contacts are closed when the wheel is in the second or third channel. 70

Transmitter

Referring now to Figs. 3 and 4, wherein a unit of the transmitter is schematically shown, the transmitter comprises preferably a bank of units, 5 each unit being substantially the same with the exception of the indentations in the periphery of cams thereof. As all units are alike in their construction, only one will be described, it being understood that a group of these units are 10 assembled on a common shaft and disposed parallel with each other. The combination composing a complete unit comprises a key lever 120, a connecting rod 121, a set of escapement fingers 122 and 123, a ratchet wheel 124, a pawl 125, a slotted disk 126, a cam 127, a drive shaft 128, a contact finger 129, a finger shaft 130, a contact arm 131 and a set of contact springs 132. The shaft 128 is driven in any suitable way, such 15 as by an electric motor, and keyed to the shaft 128 is a ratchet wheel 124, which revolves with the shaft at all times. Closely associated with the ratchet wheel on shaft 128 is a cam 127, slotted disk 126 and a pawl 125 which as shown in Fig. 20 25 are combined as one unit on a sleeve. This unit is loosely carried on the drive shaft and is held stationary by the escape fingers when the unit is not being operated. The pawl is loosely mounted on the surface of the slotted disk 30 adjoining the ratchet wheel and in such a manner that the hooked end can be engaged with the teeth of the ratchet wheel and, whereby the inside edge of the small right angle tail projection 134 on the pivot end of the pawl is parallel to, and, adjoining the slot 133 in the disk 35 126. An angularly disposed end 135 of the escape finger 122 is shaped so as to enter the slot in the disk and hold the pawl clear of the ratchet wheel, and at the same time keep the cam and the disk from rotating. Should the finger 122 40 be withdrawn from the slot in the disk, the pawl will be brought into engagement with the ratchet wheel by the pawl spring 136 and the cam unit will be carried around with the rotating shaft 128. 45

If now, the finger is released before one revolution of the disk takes place, the end of the finger will come into contact with, and ride on, the edge of the disk until such a time as it reaches the slot in the disk and the pawl thereon. Just 50 before the end of the finger again enters the slot it will engage the angle portion 134 of the pawl, which at this time covers the slot due to its being in engagement with the ratchet wheel, and, therefore, tipped at a greater angle, and will carry the same back and parallel with the slot. 55

The pawl is thus disengaged from the ratchet wheel and the finger permitted to re-enter the slot, thereby locking the disk and cam against further rotation. This operation only obtains 60 when the finger 122 is released before one revolution of the shaft 128 is completed, since if the finger 122 is held away from the disk for a greater period of time, the cam unit would make more than one revolution which is not desirable. The escapement action of the two fingers 122 and 65 123 and the pawl 125, provides for automatically insuring correct operation in this respect. The finger 122 is pivoted at 137 at its end, opposite the disk; the finger 123 is pivoted on the finger 122 at 138 about midway of its length. The right hand end of finger 123, adjoining the disk, is angularly so disposed and shaped as is the end of finger 122 so as to permit it to enter the slot in the disk and engage the end of the pawl, under certain conditions when obtained. The opposite

end of the finger is bifurcated, one fork thereof, 139, being curved upwardly and at its end is secured an end of a helical restoring spring 140, attached at its other end to a support 141 and disposed to exert an upward effort substantially 5 in a direction at right angles to the main portion of the finger 122. The other fork 142 extends toward the pivot 137. The adjustable link 121 connects the end of the fork 142 to the key lever 120, the connection to 120 occurring at a point 10 midway thereof.

If now, the key lever 120 be depressed, the link 121 will exert a downward pull on the extension 142 of the finger 123 and on the restoring spring 140 rocking the finger 123 counter-clockwise as 15 viewed in Fig. 3. The opposite end of the finger 123 is thereby raised up against the disk by the rocking of finger 123 on its pivot 138 on finger 122.

During this movement of the finger 123, finger 20 122 will remain in its normal position, due to the relative positioning of the parts, the upward pull of the spring 140 being exerted on a three point suspension, namely, the pivot rod 137 at one end, the disk at the opposite end and the pivot of finger 123 at its center. If, after the end of the finger 123 comes into contact with the disk, the link 121 is moved farther downward by depression of the key lever 120, the pivot point of finger 123 will be moved downward also, the end of the finger in 30 contact with the disk acting as a pivot. As the finger 123 is pivoted on finger 122, this operation will cause finger 122 to be drawn down and rotated on its pivot rod 137 in the left-hand end. This movement of finger 122 will effect the withdrawal of its end 135 out of the slot in the disk and free the disk 126. At the moment the finger is withdrawn from the slot 133, the pawl will be 35 spring pressed into engagement with the ratchet wheel, and thus, the cam unit will be rotated by 40 the drive shaft. When one revolution thereof is nearly completed and the finger 123 is held against the disk by the pressure on the key lever, the end 143 of the finger 123 will enter the slot 133 and effect the disengagement of the pawl 45 from the ratchet wheel, thus locking the cam unit as mentioned before. Now, the pressure on the key lever 120 being removed and the key returned to its normal position, the spring 140 will raise finger 122 into contact with the disk, after which 50 with a continued upward movement of the key finger 123 will be withdrawn from the slot 133 and through the operation of the pawl and ratchet wheel the cam unit will be advanced until finger 122 enters the slot 133 and again releases 55 the pawl and locks the cam unit.

The arrangement of the escapement as a whole is such that the cam unit will make but one revolution for each complete operation of the key lever, regardless of the length of time that the key lever is held in a downward position. The action of the two fingers on the disk and pawl is to always bring the idle finger into operative position before the withdrawal of the locking finger from the slot in the cam unit, the idle finger causing the release of the locking finger by the movement of the fulcrum points along the length of the fingers. The key lever used may be of the type common to all typewriters and requires no explanation. The cam section of the unit just referred to has a toothed edge, the teeth being so disposed thereon as to operate the contact 132 according to the impulse code to be transmitted by that particular cam. In contact with and operated by the toothed cam is one end 70 75

of a contact finger 129, this end of which holds a roller 144 for the reduction of friction between the finger and the cam. As shown in Fig. 11, the finger is constructed with a hole through the 5 opposite end through which passes a finger shaft 130. An adjusting screw 145 is preferably provided in the end projecting beyond the shaft 130. The finger has a slot 146 throughout its length receiving the roller 144 at its one end and a pin 10 147 rests within the slot at the other end of the finger. The finger is loosely mounted upon the shaft 130 and directly in line with the slot, a hole being cut through the shaft at right angles thereto, into which is secured the pin 147. The slot 15 146 is of such dimension that the pin does not come into contact with the body of the finger, in its movement on the shaft, but the pin does engage the end of the adjusting screw 145 provided in that end of the finger.

20 It can be seen that an upward movement of the finger by the cam will cause the shaft 130 to be rotated, and also that the shaft could be rotated in a clockwise direction, as seen from the right, without imparting any movement to the 25 finger. Each time that the cam is rotated the irregular surface of the cam will cause the finger to be intermittently raised to impart movement to the shaft through the screw and pin, but in the case where two or more like cam units are 30 mounted upon the same shaft, the operation of one cam and finger unit will not affect the others, as the shaft 130 can be rotated in a clockwise direction by any one unit and through the functioning of the screws and pins, the others 35 will remain stationary.

Thus, a series of impulses are communicated to the contacts 132 through any contact finger 129 from one of a number of cam units without interference. The contact arm 131 secured on 40 shaft 130 causes the contacts 132 to be operated responsive to movements of any selected finger riding on the irregular surface of a cam. This construction makes it possible to use but one set of electrical contacts for an indefinite number 45 of cams resulting in a comparatively simple but positive impulse transmitter. Shaft 128, which is the power driven shaft, is preferably equipped with bearings, not shown, as is also the shaft 130, as indicated at 154. In operating the transmitter, 50 the depression of any key will cause the cam associated with that key to make one revolution. Each cam, having a different series of teeth on its edge, will cause its associated contact finger to oscillate the finger shaft, which in turn will 55 close and open the set of contacts 132 in unison therewith. In this way the desired series of impulses, corresponding to any character, can be transmitted over a wire. A further explanation of its relation to the line and selector will be 60 found elsewhere in the description.

Paper feed and carriage return

In the typewriting portion of our improved mechanism, the carriage return and the paper 65 line feed is cooperatively effected. This part of the description will cover the paper carriage mechanism shown in Figs. 6 and 6a, which includes the carriage frame, the paper feed rolls, the carriage and paper shifting rack and gears, 70 the driving clutch, the spacing escapement gears, the paper shift ratchet and the carriage rollers and track. The paper carriage consists of two parallel end frame members, one of which is shown in dotted lines at 151 in Fig. 6a secured 75 together by connecting bars, which act also as

spring supports, stops, etc., the spacing between the frame members being sufficient to accommodate a roll of paper 152, the feed rollers 156 and 157 and the paper line spacing mechanism, the preferred relation of the equipment being indicated in Fig. 6a.

Four grooved rollers 155 are disposed one at each of the four corners of the carriage frame having the end frame members 151, to permit the frame to travel on a pair of preferably circular 10 rails fixed to the machine bed 43. The roll of paper 152 is placed upon a movable shaft 158 which is suspended on and between the end frame members 151 of the carriage, the ends of the shaft being so reduced in diameter as to enter 15 and rotate freely in a slot 159 in each end member. After the paper is placed in the carriage, the free end of the paper is directed between the two feed rollers 156 and 157, which feed and control the movement of the paper through a set 20 of vertical guides 160 that direct the paper upwards and over the top of the machine to cause it to pass between the typewheel 71 at the rear of the carriage and the inking ribbon 161 and printing hammer 297 at the front.

The paper roll being mounted upon and moving with the carriage continuously is in alignment 25 with the feed rolls and guides and, therefore, the paper will not have its edges entangled in the guides and mutilated, rendering the machine inoperative. The lower ends of the paper guides 160, as well as the inner guide 175 are so shaped 30 that the end of the paper will be directed to and between the feed rollers 156 and 157 and upward 35 through the vertical guides when the paper roll is inserted in the carriage and rotated in the proper direction.

Knobs are provided in connection with the shaft ends of the top feed roll in order to rotate 40 same when the paper is being threaded through its channel. As can be noted, although the paper might be fed into the feed rolls from the bottom, rather than from the side of the roll, this half turn of the paper around the upper feed roll takes a part of the curl from the paper and 45 leaves just enough as to cause the paper to follow over the back of the machine after it passes out of the guides at the top of the carriage.

It is evident that to reverse the direction of 50 rotation of the paper roll in the carriage would mean that the paper would travel over and in front of the carriage and keyboard, and would not only interfere with the operation of the machine but would cut off all visibility in respect to the printing. As the roll of paper is free to rotate 55 in the carriage the feed rolls 156 and 157 unwind the paper from the roll 152 and force it up through the guides 160 and 175 and out of the top of the carriage, passing the typewheel and the printing apparatus.

On one end of the feed roll shaft 156 is a ratchet wheel 162 which is engaged by a pawl 163 pivotally carried on the lever arm 164. The arm 164, pivoted at one end, terminates in a roller 165 at the other, which roller contacts 60 with the cam 166 on the carriage return rack 167. The lower end of pawl 163 rests on a pin 168 when in its normal position. The angular position of the spring 169 relative to the pawl and arm, causes the pawl and arm to be drawn 70 downward and at the same time brings the pawl into contact with the pin. The movement of the lower end of the pawl over the pin swings the upper end away from, and free of the ratchet wheel which permits rotating of the paper feed 75

rolls in either direction during the threading of the paper.

If now the roller end of the arm 164 be raised, the pawl will be carried away from the pin and the upper end of the pawl will engage a tooth in the ratchet wheel. A further movement of the arm will rotate the ratchet wheel and feed the roller until the arm movement is arrested, to move the paper up through the guides a definite distance. The number of teeth in the ratchet wheel will determine the movement of the paper since each movement of the arm turns the ratchet and roll the distance of one tooth space. To insure an accurate line shift spacing of the paper an indent roller 171 and leaf spring 60 are associated with the ratchet wheel and are adapted to center the ratchet wheel.

Mounted upon the back of the paper carriage is the toothed return rack 167 for the return of the carriage to its right hand position on the machine, effective to shift the paper each time that the carriage is returned. The rack is slotted at 172, Fig. 6, near each end and is suspended on the carriage by two screws 173 passing through the slots and into the frame end members 151 of the carriage. Through the screw and slot suspension, the rack can be moved a definite distance lengthwise along the carriage, being restorable to normal position by the spring 174. Mounted upon the rack 167 and in line with the paper shift arm 164 is a cam 166.

Each time that the rack is moved along the carriage on the screws 173 the cam will raise the shift arm by virtue of the roller carried on its end, riding up the incline on the top edge of the cam. This causes shifting of the paper in the carriage, an amount equal to one typewritten line for each movement of the rack.

When the end of the slots in the rack engage the screws 173 a further movement of the rack will pull the carriage along its track to the end of its travel across the machine. Should the carriage be in its extreme starting position on the right hand end of the machine and the rack be moved on its supporting screws the paper will be shifted up but no movement of the carriage will take place. The mechanism for moving the rack 167 to shift the paper or to shift the paper and return the carriage will now be described.

Engaged with the rack is a gear 176 combined as a unit with a helical gear 177 which rotates on a stud 178. The helical gear is meshed with a similar gear 179 on the drive shaft 180.

This gear carries two pins 181 projecting from one side thereof with which two like pins 182 in a sliding sleeve 183 are adapted to engage. The sleeve 183 is loosely carried on the drive shaft 180, but is keyed to the shaft and rotatable thereby. The key pin 184 in the hub of the sleeve extends into a slot 185 in the shaft. If the sleeve is moved along the shaft until the pins carried on the sleeve 183 engage those carried by the gear 179 the shaft will cause the gear combination 176-177 to rotate, which in turn will move the rack 167.

Engaging within a slot in the sleeve 183 is one arm of a bell crank 186 which is pivoted at the junction of its two arms. It engages a pin 187 on a lever arm 188 at the end of the second arm. The lever arm 188 is pivoted at 209 at one end and extends to a point in line with the movable rack 167 on the carriage, this extension carrying an adjusting screw 189 which contacts with the end of the rack. The lever arm 188 is also tied to the bell crank 186 by a spring 190. About

the center of the upper arm of the bell crank 186 is a pin 191 which engages a hook on the pawl 192 pivoted on the top of the armature 193. The pawl 192 has a small extension beyond its pivot point which contacts with a stop 194. A 5 spring 195 holding the pawl in engagement with the pin 191 in the bell crank 186 also holds the armature 193 in its inoperated position.

Cooperating with the armature 193 is a magnet 196 and upon energization thereof the mechanism will operate to return the carriage as will presently appear.

When the armature 193 is attracted by the magnet 196 it will, through the pawl 192, move the bell crank 186 on its pivot, to cause the 15 sleeve 183 to be moved along the shaft 180 to effect interlocking the pins 181 of gear 179 with the pins 182 of the sleeve. At the same time the lower arm of the bell crank lever 186 is raised above the pin 187 in the lever arm 188 20 and this arm will then be drawn against a pawl 197 by the spring 190. As the lever arm 188 moves over toward the pawl 197 the pin 187 will be projected under the lower arm of the bell crank 186, locking it against return to normal 25 position and locking the clutch pins into clutching engagement. The drive shaft 180 through the clutch and gears now causes the rack 167 to move the carriage, if the carriage is not in its extreme right hand position, until the end of the rack 167 contacts with the contact screw 189 of the lever arm 188.

Continued motion of the rack will move the lever arm 188 back to its normal position, thereby increasing tension of the spring 190 and freeing the lower end of the bell crank lever 186 from the locking action of the pin 187, releasing the bell crank which will be returned to normal position, and disengaging the clutch and locking the lever arm 188 in normal position.

Near the extreme end of the stroke of the armature 193 above referred to the extension of pawl 192 makes contact with the stop member 194 giving the hooked end of the pawl 192 a downward motion to disengage the hooked end 45 of pawl 192 from the pin 191 in the bell crank, freeing the same to permit it to return to normal under the control of lever arm 188.

By virtue of this disengagement of the pawl, current through the magnet 196 may be prolonged indefinitely without interfering with the disengaging of the clutch. Provision is also made for the engagement of the clutch elements 181-182 when the carriage has reached its limit of movement across the machine toward the left and it is required that the carriage be returned to the opposite end by the motor, not shown, driving shaft 180. This is accomplished by actuation of the lever arm 198 and the connecting rod 199. When the carriage travels to the left end of the machine the fixed rack 200 comes into contact with the upper end of the lever arm 198, moving it against the power of the spring 201. Connected to the arm 198 and bell crank 186 is the connecting rod 199, one end of which is hooked into a hole 220 in the arm 198 and the other end of which is passed around the upper arm of the bell crank lever 186 and has its extreme end then bent at a right angle, to engage the bell crank to move the same whenever pulled by the arm 198. As the carriage moves along, the rack 200 will move the arm 198 and the rod 199 until the hooked end 42 of the rod 199 operates the clutch mechanism in the same manner

as before described for operation by the movement of armature 193.

By operating a set of contacts 202 by movement of the lever arm 198, the carriage may also 5 be returned by the energization of the magnet 196 by current caused to flow through normally open contacts of the set 202. By energizing the magnet 196 the carriage can be brought to its starting position at any time, or it will be always 10 automatically returned to this position upon reaching the extreme opposite position on the machine; also the paper will be shifted upward each time that the carriage is moved to return it or as many times as is desired after the carriage 15 has reached its limit of return travel by energizing the magnet 196 a corresponding number of times.

To prevent the paper carriage from spacing when the carriage and paper are being shifted, 20 the small bell crank lever 197 above mentioned is positioned between the fixed rack 200 on the carriage and the lever arm 188. At such times when the lever arm 188 is in an operated position, during the time the clutch is engaged, the 25 lever arm will contact with the projection on the bell crank lever 197 and by rotating on its pivot, the bell crank lever will engage with teeth on the fixed rack 200 with its hooked end and prevent it and the carriage from moving in a spacing 30 direction, but as the hooked end of the bell crank lever 197 has a beveled end face it will not arrest movements of the carriage in the other direction.

While the carriage is being returned to the 35 start position, the beveled end of the bell crank lever will cause it to ride over the teeth on the rack, the spring 190 acting as a tension member through the lever arm 188.

The following description applies to the driving 40 of the carriage in the spacing direction. Attached to the fixed rack 200 on the paper carriage is one end of a tape 203, the other end of which is wound around a tape drum 204, carrying a gear 205. Both gear and drum rotate on 45 the stud 206.

Meshed with the gear 205 is a sector gear 207, pivoted at its lower end and operated by the spring 208. By virtue of the pull exerted by the spring 208 the sector gear 207 will exert a rotational effort upon the gear 205 and the drum 204, winding the tape on the drum and pulling the carriage across the machine when released by an escapement mechanism comprising a double acting pawl 41, and escape wheel 231. The angular 55 position of spring 208 in relation to the sector gear 207 is preferably such that when the sector gear is at that one extreme position wherein the spring 208 exerts the least effort upon it, a line through the pin 219 and the center of the sector 60 pivot stud will be disposed substantially at right angles to the spring 208.

Such an arrangement results in the spring 208 exerting an effort through greatest leverage, upon the sector gear at the time that the spring 65 is extended the least and, results in a more even torque being applied to the drum 204 by the spring at all points in its rotation, causing the tractive effort exerted upon the carriage by the spring to be nearly equal throughout its travel. 70 Supported upon the fixed frame of the machine, is the escapement unit comprising a gear wheel 230 meshed with the rack 200 and having a ratchet wheel 231 rigidly secured to one face thereof. This gear and ratchet wheel rotate on 75 a stud 211 fixed to the machine frame.

Co-operating with the ratchet 231 is the double acting pawl 41 which permits the ratchet wheel to advance one tooth for each oscillation. This pawl is operated in one direction by a spring 233 and in the other by the armature extension 83 as shown in Fig. 1. Upon armature 83 being operated by its magnet 89, the escape or ratchet wheel 231 will be advanced one tooth as will the gear 230, the rack 200 and the paper carriage, the stepping of these parts When the carriage is being returned by power of the motor as before described, to the starting position, the pawl and the ratchet wheel will, through their angle of contact, act in a well-known manner as a free escapement and exert but little retardation on the carriage. Fig. 6a shows the relation of the paper carriage parts to the typewheel 71, printing hammer 297 and carriage supporting tracks. The paper can be spaced upward, the carriage can be returned to the starting position, and the carriage moved in a step-by-step manner across the machine as the printing goes on, every operation being accomplished automatically or manually as 25 30 35 40 45 50 55 60 65 70 75 80 85 90 95 100 105 110 115 120 125 130 135 140 145 150 155 160 165 170 175 180 185 190 195 200 205 210 215 220 225 230 23

the shafts 250 and 251, and the gears are carried with the shafts at such time.

In alignment with the spur gears 245 and 246 carried on the lower ends of shafts 250 and 251, 5 are a pair of spur gears 257 and 258 which are so disposed that when the gear 246 is in mesh with the gear 258, the opposite set of meshable gears 245 and 257 will be demeshed. Contrariwise when the gears 245 and 257 are in mesh the 10 gears 258 and 246 will be demeshed.

The gears 257 and 258 are meshed with and driven by a train of other gears from a common driving pinion 259. The intermediate gear for the gear 257 being shown at 260, and for the gear 258 there is provided an interconnecting gearing comprising a pinion 261 having an enlarged gear portion 262, affixed thereto and a pinion 263 intermediate the gear portion 262 and the pinion 259. Non-rotatably secured on 20 the gear pinion 259 is a ratchet wheel 264. Journaled on the shaft carrying the pinion 259 and the ratchet wheel 264 we provide a gear 265 in mesh with a rack 12 rigidly mounted upon the front of the paper carriage and longitudinally 25 reciprocable therewith a pawl 266 is pivoted at 267 upon the upper face of the gear 265 as is also a leaf spring 268 which engages with the ratchet wheel 264. This arrangement permits relative rotation of the gear pinion 259, with respect to 30 the gear 265, in but one direction. By virtue of this arrangement the pinion 259 is caused to rotate in one direction, when the gear 265 is rotated, but upon opposite rotation of the gear 265 no rotation of the pinion will occur.

35 Therefore when the carriage to which is secured the rack 12 is moved in a spacing direction both trains of gears meshed with the pinion 259 are driven thereby but when the carriage is returned to start the printing of a new line there 40 will be no driving of the pinion 259 and the trains of gears in mesh therewith. To more positively prevent improper rotation of the trains of gears upon a return movement of the carriage, because of possible frictional effect in the escapement 45 comprising the pawl 266 and ratchet wheel 264, we provide an additional spring pressed pawl 269 to prevent rotation of one of the gears in one of the trains, here shown as the gear 263.

The above arrangement is provided for the 50 purpose of preventing rotation of the ribbon spools 241 and 242 during the return movement of the carriage and to provide for a step by step rotation of the ribbon spools as commonly required in typewriting apparatus during spacing 55 movements of the carriage, and upon spacing movements that spool whose driving pinion 245 or 246 is in mesh with the intermediate trains of gears driven by the pinion 259, it will be rotated to wind the ribbon 161 upon it.

60 Parallel to the shafts 250 and 251 are provided the shafts 272 and 273 which are journaled at each end to the main frame 40. Attached to the lower end of the shafts 272 and 273 in proximity of the fixed bearings 271 are a pair of short lever arms 280 and 281. Carried by the upper end of each of the shafts 272 and 273 are arms 276 and 277 having rollers journaled in the outer ends. These rollers 278 and 279 bear upon the ribbon rolls 241 and 242. The rollers are 65 held in engagement with the ribbon rolls by means of coil springs 274 and 275 substantially about the upper part of the shafts 272 and 273. The springs are secured at one end 38 and 39 to the main frame and are coiled about the 70 shafts and are secured to the opposite end of the

roller arms 276 and 277. The shafts 272 and 273 being parallel to the shafts 250 and 251, and the arms 276 and 277 being of suitable length, the rollers carried by the arms 276 and 277 will swing toward the center of the ribbon spools, and are 5 caused to follow the ribbon during the winding and unwinding of the ribbon spools on or off by the action of the springs 274 and 275. As shown the ribbon rollers are supplied with the maximum and minimum diameter of ribbon rolls 10 thereon. Ribbon roller 241 is at the minimum diameter and ribbon roller 242 is at the maximum diameter. It will be seen that any change in the diameter of the ribbon on the rolls will exert varying movements upon the arms 276 and 15 277 which in turn cause the shafts 272 and 273 to be rotated, transmitting a pivotal movement to the lever arms 280 and 281.

Carried by the plate 254, and in close relation with the gears 257 and 258, are two pawl members 282 and 283. The pawls are normally held in operative position against the stop pins 284 and 285 by the spring action exerted by the flat springs 286 and 287 secured to the plate 254. The pawls are pivoted to the plate 254, the outer 20 ends being shaped so as to provide a lug on one side thereof to be engaged by the short arms 280 and 281 while the opposite sides of the pawls are provided with a sharp tooth. The outer ends of the pawls terminate in a projection on which 30 the springs 286 and 287 exert their force to retain the pawls in inoperative position.

As shown the plate 254 is in its maximum left hand position relative to its support. In this position the tooth on the pawl 282 is disposed in 35 substantial radial alignment with the center of the gear 257, while the pawl 283 in its shifted position is left of the radial center of the gear 258. If the gear 257 is rotated by the carriage, and in the direction of the arrow, and if the pawl 40 282 is pushed against its spring and into engagement with the gear 257 this gear will draw the pawl along with it until a time is reached when the pawl is released. The pawl being attached to the plate 254 it too will be moved in 45 the direction of the arrow by the active gear until the pawl is released.

Engagement of the pawl with the gear wheel is brought about by the roller arm 276 contacting with the ribbon spools 241, so that when the 50 diameter of the ribbon on the roll reaches a predetermined minimum the roller arm will transmit a rotary motion to the short lever arm 280 so as to abut against the lug 36 on the pawl 282. The rotary motion to the short arm is transmitted 55 by the shaft 272 herebefore described in detail. The same operation is effected by the ribbon roll 242 and roller arm 277 on the pawl 283 when the ribbon has been exhausted to the minimum from the ribbon roll 242.

Heretofore we described the engagement of the pawl and the gear whereby the plate is shifted in the same direction as the gear is rotated. Inasmuch as the plate and pawl move more rapidly than the lever arms 276 and 277 the pawls are carried away from the gears 257 and 258 by the force exerted by the springs 286 and 287 when the short arms are moved away from the pawls, and the pawls are accordingly returned to inoperative position against the stop pins 284 70 and 285.

To overcome any friction between the pawl and the gear wheel we have provided a means to cause disengagement. Preferably the means provided consists of a pawl 290 pivoted to the 75

main frame of the machine and held in one of two notches 238 and 239 provided on one side of the plate 254, by the force exerted by the spring 289 supported on the main frame of the machine. 5 It will be seen that shifting the plate 254 in either direction by the gears 257 or 258 shifts the pawl 290 from one notch in the plate and the spring forces the same into the other notch. In this manner the plate 254 is held in position 10 until the ribbon is exhausted from one of the ribbon rolls. It will also be seen that any friction between the pawls and the gears while in engagement with each other, will be overcome by the snap action of the pawl 290 in entering 15 one of the notches on the plate 254. In this way the plate is carried ahead faster than the speed of the gear thereby allowing the pawls 282 and 283 to return to inoperative position.

When the plate 254 is shifted to the left the 20 gears 246 and 258 are in mesh while gears 245 and 257 are separated, likewise the shifting of the plate 254 to the right will cause gears 245 and 257 to mesh, while gears 246 and 258 are disengaged. From the foregoing it is evident that as 25 the gear trains herebefore described, are rotated by the carriage rack, and the gears 245 and 246, when either is in engagement with the train gears, the ribbon rolls will be rotated in one direction or the other, depending upon which of the gears 30 referred to are meshed, thereby causing the unwinding of the ribbon from the free ribbon roll and winding the ribbon on the driven roll. It will be noted that, although one ribbon roll is termed a free ribbon roll, the roller arms 276 and 35 277 act as brakes by virtue of the tension exerted on the roller arms by the springs 274 and 275.

The winding and unwinding operation of the ribbon spools takes place in either direction until a time when the ribbon on the free ribbon roll 40 reaches a predetermined diameter, at which times, the reversing mechanism herebefore described automatically shifts the gears 245 and 246.

A side view of the printing apparatus is best 45 shown in Figs. 5a and 6a and will be hereinafter more fully described.

The ribbon is guided through a pair of guide slots provided in the ribbon elevator 35 and in the upper portion thereof. The ribbon elevator is 50 supported by a pair of parallel arms 305 and 306 which are pivoted at one end 304 to the main frame of the machine and at their opposite ends are secured to the elevator 35 by studs 295. Carried by the elevator 35 and above these studs are 55 two small rolls 294 adapted to rotate on a vertical axis to reduce the friction between the ribbon and the guide slots as the ribbon passes the type wheel.

In normal position the elevator used is in such 60 a position as to leave the top of the ribbon slightly below the point of contact with the paper 33 which receives the printed characters. When the elevator member 35 is raised upward against the stop pin 296 the ribbon will be carried upward in 65 direct alignment with the characters on the type-wheel 71. Thus a clear vision at all times may be had by the operator, except when the printing operation is taking place. The elevator member 70 35 is forced upward into printing engagement by the action of the printing hammer arm 297, armature arm 307, and magnet 300, which will be hereinafter described more in detail.

Disposed below the elevator 35, substantially at 75 right angles thereto is a curved armature arm 307

pivotedly supported on a shaft 308 and adapted to support on its outer end a magnetic pole piece 299. Upon the end of the armature arm 307 is pivoted the printing hammer 297. Disposed below and in alignment with the pole piece 299 is an 5 operating magnet 300 supported on the main frame in such a way that the energizing of the same attracts the pole piece 299 downward rocking the arm 307 causing the printing hammer 297 to be swung upward on its pivot 34 to effect the 10 printing on the paper 33.

The printing hammer is composed of two L-shaped pieces 302 one of which appears in the drawings joined at the ends of their long arms and secured to the hammer head 297 in any well 15 known manner. The shorter arms of the L-shaped members 302 have bearings 303 adapted to support a roller 301 journaled to freely rotate therein. The long arms of the members 302 normally rest on the shaft 308, adjacent the hammer 20 head 297. A screw 309 is also provided to limit the downward movement of the armature and hammer, and is preferably adjustable to vary the movement of the armature arm 307.

The action of the above in the elevation of the ribbon and printing hammer is as follows:

When the magnet 300 is energized the armature pole piece 299 is drawn downward raising the curved end of the armature and the hammer. If the operation were slow and the elevator relatively heavy, the roller 301 journaled in the short end of the arm 303 of the hammer, would be forced under the spacing stud 293 and the hammer would be raised up and against the paper at a point below the proper printing position, 35 and the ribbon would not have been raised.

The above described operation of the combined unit is effected by the speed of operation, and the relative positioning of the different co-operative parts. The arms of the hammer unit are set at such an angle from the vertical and the hammer is made of such a weight, that a certain resistance to the movement thereof around the pivot 303 results. The angular relationship of the roller 301 to the spacing stud 40 45 293 is substantially 45 degrees which tends to cause an upward thrust on the elevator 35.

Cooperating with the previously mentioned factors is the elevator which should be so proportioned in weight as to offer a certain resistance to the raising of the hammer. When its function is completed, the quick movement of the armature 307 by the magnet 300, is resisted by the angle and weight of the hammer and the 50 55 angular relation of the roller 301 and the stud 293. The force resulting from this reaction is all applied to the stud 293, accordingly the elevator 35 will be raised to a position governed by the stop 296. At the end of this movement the relation of the roller 301 to the stud 293 is such as to cause the roller to travel under the stud 293 60 causing the upwardly swinging action of the hammer on its pivot toward the typewheel 71.

As the hammer is raised and rotated around 65 its pivot the angle between the roller and the stud gradually decreases until a point is reached where the movement of the roller is in a horizontal plane. At this point the roller will ride under the stud while the hammer will continue its arcuate movement until it strikes the type wheel 71.

It will be seen that the action of the roller and the stud forces practically all of the power to initially lift the ribbon elevator. The hammer is then started slowly in its travel toward 70 75

the typewheel, the speed being increased until the roller leaves the stud and the hammer completes its stroke. In this way the ribbon is raised up in front of the type wheel while the printing hammer is caused to strike the ribbon, forcing it against the paper causing the type wheel to impress a character on the paper.

The relative positions of the various parts of the units just described are best shown in Figs. 5 and 5a.

The ribbon and the printing mechanism is preferably located centrally and in front of the paper carriage. The ribbon elevator 35 and the armature arm 307 spanning the paper roll 152 on the carriage bring the ribbon and the hammer in close proximity of the typewheel as will be seen by reference to Fig. 5a.

The control of the electric circuit to the magnets 300 will be hereinafter fully described.

20 Motor and line switch

Included in the machine is a mechanism for the switching on and off, of the motor, the switching of the line circuit to the sending, receiving and stopped condition, and a time limiting or time delay action for stopping the machine automatically after a predetermined time period has elapsed. This unit is power driven with the exception of the two manually operated buttons provided at the right and is controlled by the buttons, the two magnets and paper carriage.

The power employed to drive the machine is preferably an electric motor. Suitable switches are provided to start and stop the motor at times desired so that the machine does not operate continuously but is always under the control of the operator who may be at any machine of the system. The motor switch heretofore referred to is of the toggle type, and the switch blade is operated in one direction by the motor and is returned by a spring. We have arranged preferably two L-shaped levers 310 and 311 which are supported on a common pivot 312, one of these members extending upwardly and to the right while the other member extends upwardly but horizontally in the opposite direction. The L-shaped lever 310 is provided on its lower end with an insulator portion upon which is fastened a contact plate 61. When in the operative position shown the contact plate 61 engages two fingers 314 completing an electrical circuit through the fingers 314 to the motor.

The right hand portion of the L-shaped lever 311 is tapered downwardly to insure engagement with the armature 315. Disposed at equal distances between the ends of the L-shaped levers 310 and 311 are preferably pins 316 and 317 which support a spring 318 in its stretched position. The function of the lever 311 is to raise the spring 318 upwardly until it passes above the pivot 312. This action will give to the lever 310 a snapping upward movement and if the lever 311 is lowered so that the spring 318 passes below the pivot stud 312, the L-shaped lever 310 will be snapped down into contact with the fingers 314 again.

The vertical section of the L-shaped lever 311 extends above the periphery of the gear 319. Carried on the face of the gear 319 is a pin 320 which is carried around as the gear 319 is rotated in the direction of the arrow and which is capable of striking the L-shaped lever 311 and moving the same to the left until the pin passes over the end of the L-shaped lever 311. As the

pin 320 moves the L-shaped lever 311 to the left, the horizontal section of the L-shaped lever 311 will be raised on its pivot 312 above the armature 315. The end of the bevel portion of the L-shaped lever 311 then passes into the notch in the armature 315 and the armature 315 will be drawn over by the spring 321 and caused to pass under the lever 311 locking the same in this position. Simultaneously the pin 320 on the gear 319 passes the point of contact with the L-shaped lever 311. This operation opens the motor switch and it is locked by the armature 315.

Carried by the main frame of the machine and the L-shaped lever 311 is a spring 322 which is secured to the L-shaped lever near its bevel end. The function of the spring 322 is adapted to draw the L-shaped lever 311 downwardly when it is released by the armature 315.

The armature 315 is operated by energizing the magnet 323. When the armature is moved to the right it will release the L-shaped lever 311 which will be drawn downwardly by the spring thereby closing the switch. The movement of the L-shaped lever 310 in opening and closing the switch also operates the contacts 324 through the insulating stud 325. In opening the switch only the L-shaped lever 310 operates a horizontal bar 326. The function of the bar 326 will be hereinafter more fully described.

Associated with and driven by the motor is a gear 327 and a train of gears 328, 329, 330, 331, and 332, the ratio of these gears being such as to give a predetermined reduction in speed between gear 328 and 332. The driving gear 327 being engaged directly with the gear 328, an operation caused by the gear 328 will be fairly fast relatively to the speed of the gear 327 and any function caused by gear 332 will be much slower depending upon the gear train ratio selected for a definite interval of time.

Disposed directly in front and below the axis of the gears 328 and 332 are two gears 319 and 333 all of equal size. These gears are intermittently meshed with the two driving gears 334 and 335 and are driven when so meshed by the companion gears 328 and 332. As the three sets of gears referred to above operate in a similar manner their locking and releasing operations are alike. The functions of gears 329, 319, and 334 will now be described.

Gears 328 and 319 are mounted on parallel axes of rotation, each facing the other with a slight clearance between them so that when the gear 334 is brought into mesh with the two gears 328 and 319, by swinging on the pivot 336, the lower gear 319 is driven by the upper gear 328 through the gear 334 as best shown in Fig. 7a. It will be seen that gear 319 receives an intermittent rotary motion by being meshed or unmeshed with the gear 334. Relative spacing of the gears 328 and 319 is important in this operation. It will be seen that if the gears were in alignment and the gear 334 was in engagement with the gears 328 and 319 the angle of the teeth on these gears when in contact with each other, and when power is applied to gear 328, and a load applied to gear 319 the idler gear 334 would be forced out of engagement with the other gears 328 and 319. Should the centers of the gears 328 and 329 be spaced a given distance apart the angles of the teeth on the gears, relative to each other, would be in opposite order and the idler, 334, would be drawn closer between the gears 319 and 328 and ultimately locked in this position while power was

30

35

70

75

applied to gear 328 and a load maintained on gear 319.

Any action of this kind by the gears 328, 319 and 334 is overcome by spacing the driving and the driven gears in such a manner as to bring the angles of contact between the teeth of the gears and of the idler into substantially parallel planes. This results in the idler gear when released, meshing with the gears 328 and 319, and remaining 10 in meshed position until the load is removed or the gears unmeshed. The difference in the angle of contact of the gear teeth is substantially zero and the slight locking which takes place is not to such an extent as to render the separation of the 15 gears difficult.

When the gear 334 is meshed with gears 328 and 319, it is necessary that the idler gear become properly meshed with both the gears 319 and 328. This action is assured by placing the arc through 20 which the center of the gear 334 travels at such position that the gear 334 will always contact with the driving gear 328 first which will draw the idler gear 334 into mesh with the driven gear 319. Gear 334 is loosely journaled in the upper end of a 25 bell crank lever 337 which is pivoted to the main frame at 336 and swung to the left by a spring 338 and in the opposite direction by a pin 339 carried on the bar 326.

The bell crank lever 337 is beveled at the end of 30 the horizontal section which is engaged by the armature 340. The armature normally holds the bell crank lever 337 in a position disengaging gear 334 from gears 328 and 319. Should the lever 337 be released by the armature 340 at a time when 35 the motor switch is closed and gear 328 is being rotated, the spring 338 on the bell crank lever 337 will bring the gear 334 into mesh with the gears 328 and 319. Gear 319 will now be rotated in the direction of the arrow, carrying the pin 320 40 around into contact with the upper end of lever 311. Continued rotation of gear 319 will open and lock the motor switch as heretofore described and simultaneously the vertical section of the lever 310 strikes a pin on bar 326 shifting the bar to the 45 right. This movement of the bar 326 by means of the bell crank lever 337 disengages the gear 334 from its companion gears. Bell crank lever 337 will be locked in this position by the armature 340 and the spring 341. In this manner the 50 motor switch can be closed by the energizing magnet 323 and is opened by energizing magnet 342.

Referring more particularly to the time limiting feature for the opening of the switch which functions substantially the same as the motor switch proper, in regard to intermittent drive by the gear train, through the idler gear 335 and gears 332 and 333. The idler gear 335 is carried on a vertically disposed lever 343 which is pivoted at its 55 lower end 344 to the machine frame and extends upward in line with the fixed rack 200 on the paper carriage 151. The lever 343 retains the gear 335 in engagement with gears 332 and 333 by the action spring 346 during the time it is not in 60 contact with the rack 200, or shifted to the right by the pin 347 on the bar 326. The engagement of gear 335 in mesh with gears 332 and 333 slowly rotates gear 333 at this end of the gear train at a 65 reduced speed in the direction of the arrow.

Upon the face of gear 333 a stud 348 is carried 70 which is held against a stop lever 349 by means of preferably the spiral spring 350, one end of which is attached to the pin 348 in the gear wheel 333 while the other end is secured to the

stationary bearing 351 upon which the gear 333 rotates. It will be seen that should the gear 333 be turned in a clockwise direction and released, it will be returned to its normal position with the pin 348 against the stop lever 349 by the 5 spring 350. Rotation of the gear 333 far enough, will cause the pin 348 on this gear 333 to strike the upper end of lever 352, pivoted at its center to the main frame of the machine, thereby contacting its lower end to operate the armature 10 lever 340 to the right.

Operation of the armature 340 by the lever 352, will release bell crank lever 337 thereby opening the motor switch as heretofore described. With the operation of the switch lever 310, the 15 bar 326 is shifted to the right and the pin 347 in the bar 326, to the left of lever 343, will shift lever 343 and, in turn the gear 335 out of engagement with its associated gears. As soon as gear 335 is released from gear 332 gear 333 will 20 be returned by the spring 350 to normal position, and gear 335 will be held out of engagement with gears 332 and 333 as long as the motor switch is open. It will be re-engaged with gears 332 and 333 the moment the switch is closed provided 25 the paper carriage is not in the starting position.

Each time the paper carriage is returned to starting position by the motor, the rack 200 will strike the lever 343 and dis-engage the gear 335 from gears 332 and 333 allowing the gear 333 30 to return to normal position. The motor has now been started by the operation of the motor switch and consequently the switch member 310 will release bar 326 and the spring 353 will move the bar 326 to the left. The lever 343 is 35 then released by the pin 347 in the bar 326 and the gears 332, 333, and 335 are meshed and slowly rotate the gear 333.

Assuming that the rotation of gear 333 will bring the pin 348 into contact with the member 40 352, thereby opening the motor switch at the end of a five minute period of time for example, if return of the paper carriage does not take place during this time, the machine will be automatically stopped. However, if carriage is 45 returned to its starting position at any time during this five minute period of time, the carriage will strike the lever 343; the gear 333 will be returned again to its normal position. There is preferably a five minute interval of time between 50 the last operation of the carriage, the starting of the machine, and the moment when the machine will be automatically stopped. The machine will continue to run, if the printing is not stopped, for a greater period of time than that 55 for which the time limit mechanism is set. The interval of time for which the automatic operation of the motor switch is set can be varied by changing the distance between the pin 348 and the stop lever 349.

Any suitable means may be provided to mount the pin 348 so that its position may be adjustably varied by minute amounts. A parallel motion is given the bar 326 by pivotally supporting it on preferably two links 354 and 355 at each of its 60 ends. These links are pivoted upon the frame of the machine. Mounted upon the same pivot journaled with link 354 is a hooked pawl 356 with three extension arms, the lower arm being turned at its extremity at substantial right angles 65 to and in alignment with the link 354, the end of the upper arm being in cooperative relation with the button 357. Both the bar 326 and the pawl 356 are operated in one direction by the spring 353. When the bar 326 is moved to the 70 75

right, the link 354 will raise the hooked end of pawl 356. The pawl 356 can also be operated by the button 357 without rocking the bar 326.

Stopping the motor will shift the bar 326 to a right hand position accordingly releasing gears 334 and 335, and raising the hook on the pawl 356 above and clear of the upwardly central projecting contact 358 in the group 359. The right hand contacts in this group will be closed and the left hand contacts will be opened. As described in another part of the specification closing the left hand contacts of group 359, completes the line circuit through magnet 323 and the line battery. Energization of magnet 323 by the line battery operates the motor switch.

The contacts of group 359 are operated by the starting button 360, which, when pressed into engagement with the long contact spring 358 will bring the end of the spring in engagement with the hooked end of the pawl 356 and simultaneously with the moment of contact between the springs, the motor switch will operate to allow the hook on the pawl 356 to drop and hold the contacts in position shown in 8a while the start button 360 is released.

The contacts are held in this position as long as the machine is operating as the transmitting machine. This position is also maintained until the contacts 359 are released by manually actuating the transfer button 357 which connects the machine for receiving only, or when the motor switch is operated by other means as mentioned otherwise. Figure 7a is a side view of the idlers 334 and 335 and their companion gears. A full detailed description of operation of the complete unit in co-operation with the rest of the machine having been given in another portion of the specification.

Line circuit and operation

The two line circuits are best shown in diagrammatic views Figs. 8 and 8a. Fig. 8 has one line relay which energizes a secondary circuit of the machine when sending and receiving, while Fig. 8a has a separate line relay for sending and for receiving which will be hereinafter more fully described. The use of two relays is advisable in cases where there is considerable leakage in the circuit between two machines, as the individual relays can be adjusted to suit the condition under which they would function when used for one operation only.

The source of current is preferably at the transmitting end of the system. The relay at this end is subjected to varying operating characteristics different from that of the receiving relay at the opposite end of the line.

Only in cases of extreme line leakage is the circuit of Fig. 8a necessary. The operation is the same in both circuits with the exception of the dividing of the incoming and outgoing impulses between relays 361 and 362 in Fig. 8a. At 364 and 363 is represented the line terminals of the machines by which they are connected. Dotted lines representing line circuit conductors 701 and 702 interconnecting the circuits of Fig. 8 and Fig. 8a, indicate how two machines comprising transmitting and receiving elements may be interconnected by line conductors. Either of the machines may be of the two-relay (Fig. 8a) or one line relay (Fig. 8) type.

The transmitting and receiving circuit is completed through the two machines. When a machine is not in use, the circuit can be traced as follows; from terminal 363, through conductor

365, motor switch magnet 323, conductor 368, contacts 324 and 367, conductors 369 and 370, contacts 359 and 358 and then from conductor 373 to terminal 364. This is the normal circuit when the machine is idle. Should current now be supplied to terminals 363 and 364 from another machine, the trip magnet 323 of the motor switch will be energized, the insulator portion 325 of the motor switch will reverse contacts 313, 367, and 324. Reversing the contacts of group A will complete the circuit for receiving, from conductor 365 through conductor 376, contacts 313 and 367, conductor 368, line relay 361 and conductors 377 and 370, as heretofore described.

The contact group A short circuits the line relay 361 and closes the circuit through trip magnet 323 when normal, and the reversal of the group A by the motor switch short circuits trip magnet 323 and closes the circuit through the line relay 361. When current is supplied to the terminals at this time, the line relay 361 will be operated by the received impulses and will close a local circuit in the machine.

Reviewing the foregoing when the machine is idle, trip magnet 323 is connected into the line circuit, and an incoming impulse will cause the trip magnet to release the motor switch, starting the motor and the machine; the switch 367 will cause reversal of the contact group A, short circuiting the trip magnet 323 and finally connecting into the circuit line relay 361.

The resistance of magnet 323 and relay 361 being the same the switching arrangement makes it possible to change from one function to another without any change in the loop resistance of the line circuit, and two or more machines can be switched in or out of the line circuit without a change in the value of the line resistance.

The line circuit and its equipment, as just described, applies to the machine acting as a receiving machine and being controlled at one end of a circuit by a transmitting machine at the other end of the circuit. At the transmitting end, the circuit through the machine, when in operation, differs from that of the receiver because the transmitter unit must be included in the circuit. The setup and operation of the circuit and apparatus in the transmitting machine follows, when two machines are connected together, but idle, the line complete through the trip magnets 323 of each machine. When it is desired that the machines be started, current is supplied to the line momentarily to operate the motor switch trip magnet 323. This is accomplished by the operator pressing the start button 360 which must be operated to its limit of movement thereby opening contacts 358 and 359 and closing 372, 358, and 379.

The line circuit is now complete in both machines from terminal 363 through conductor 365, trip magnet 323, conductors 380 and 368, contacts 367 and 313, conductors 369 and 395, line battery, conductors 391 and 392, contacts 372 and 358 through conductor 373 to terminal 364. The current from the battery 374 will operate the trip magnets of both machines, and the motors will be started.

In the receiving machine, only the reverse operation of the contact group A will occur when the motor switch operates, but at the transmitting machine, together with the operation of the contact group A, the pawl 356 releases the hooked end so as to overlap the upper end of contact 358. When the pressure is removed from the button 360 the spring contact 358 will engage the

pawl 356, opening contacts 372 and 379 but keeping contacts 379 and 358 closed. The contacts 372 and 379 when closed, short circuit the open contacts 132 on the key transmitter completing the line circuit through the battery, but when the button is released and the pawl 356 engages the contact spring 358, as shown in Fig. 8a, the transmitter contacts 132 will be connected in the line, from terminal 363 through conductor 365 and 376, contacts 367 and 313, conductor 368, relay 361, conductor 395, battery 374, conductors 391 and 396 to the transmitter contacts 132, from contacts 132 through conductor 397, contacts 379 and 358 and conductor 373 to terminal 364.

In the manner set forth the line relay is the same both for the sending and the receiving machine, but the transmitter contacts and line battery are connected into the line circuit at 20 the transmitting machine. When two complete machines are connected to a line, either machine can be set up as a transmitter or receiver depending upon which of the machines the starting button 360 is pressed. The transfer button, 357 25 makes possible the quick change in the line circuit from transmitting to receiving while the machines are running. When the machines are in operation but the transmitter keys of the sending machine are not being operated, the 30 transmitter contacts 132 remain open thus opening the line circuit. If while a message is being received from the transmitting machine should the receiving operator desire to stop the transmission of the message, the starting button 360 35 is pressed. This, through its contact group B, opens the line circuit at the contacts 359 and 358, at the receiving machine. This stops all transmission over the line and indicates to the transmitting operator to set his or her machine for 40 receiving.

This is accomplished by operating the transfer button 357 which trips the pawl 356 and allows contacts 358 and 359 to complete the circuit from terminals 364 to the relay 361.

Manipulation of buttons 360 and 357 allows 45 for transmitting correspondence over a line in either direction at will. As stated heretofore, circuits in Figs. 8 and 8a are similar except as to the relay 361 which is reversed with respect to conductor 395 as shown in Fig. 8a. The relay 362 being added to the conductor 398 in the circuit of Fig. 8a. In this arrangement, relay 361 is short circuited and relay 362 operates in the transmitter circuit when sending, and when 50 receiving, relay 361 is connected in the line circuit and relay 362 is connected in the open transmitter circuit. The machine is stopped by sending a particular series of impulses over the line circuit by the transmitter which operates 55 magnet 342 (Fig. 7), indirectly causing the motor switch to open. In Fig. 8a, the contacts or relays 361 and 362 are preferably placed in multiple.

The opening of the motor switch, through the insulator 325 reverses the contact at "A" 65 and releases the pawl 356 causing reversal of contact "B". It is apparent that the opening of the motor switch puts the line circuit and apparatus in its normal or inoperative position ready for the starting impulse at the desired 70 time.

Machine circuit and operation

The circuit of the complete machine is preferably divided into three divisions viz; the line 75 circuit that has heretofore been described, the

first secondary circuit that is controlled directly by the contacts of the line relay, and the second local circuit that is controlled by the contacts of the slow release relay and the cam or armature operated contact groups. The first secondary circuit is best shown in Figure 9, in heavy lines and designated circuit "A". The other circuit is shown in light lines and designated circuit "B".

The power supply for the local magnets is received from the generator 407 coupled to and driven by the motor, not shown, which has been heretofore mentioned as the source of driving power for the machine. The line relay through the conductors 400 and 401 receives the impulses 10 set up by the transmitter, and through the energizing of the armature 403 to swing contact 63 into closed or opened position with relation to the second circuit through the magnets 88, 87, 15 and 114 and the generator 407 in unison therewith.

Magnet 88 oscillates finger 79 on long impulses only. Relay magnet 114 is rendered slow-releasing by short circuiting one or more turns 20 of its winding, or otherwise, and functions to 25 keep the second local circuit open during the reception of a series of impulses.

The second circuit can be traced from the line relay contact 63 through conductor 413 circuit 30 "A" to conductors 408 and 409 where it is divided into a multiple circuit through magnets 88 and 87. Conductor 410 connects magnet 88 and the slow release relay 114 through conductor 411, generator 407 and conductor 412, to armature 403 of the line relay. A combination of 35 impulses from the transmitter to the line relay 402 will set up a like series of impulses in the local circuit, all impulses operating magnet 87 and allowing the typewheel to advance one division for each impulse. All long impulses will 40 operate magnet 88 which shifts the escape finger 79 and rotates the typewheel 71 the same or a greater number of divisions than does the magnet 87, and also controls the channel position 45 of the typewheel 71.

Relay 114 is also effected by all the impulses, but due to its low release action it will remain 50 operated during the reception of a series of impulses keeping the second local circuit open during this period and stopping the printing or other functions. During the time when no impulses are being received, cam 109 keeps the armature 113 in operative position, opening the second local circuit through contacts 112. The foregoing 55 action saves time and the operation is more positive. The armature 113 is always in the operated position when the first impulse of any series energizes magnet 114 and it is only necessary that the armature be held in this position during the first impulse by cam 109, the remainder of the series holding armature in attracted 60 position through magnet 114.

Cam 109 only engages the armature arm 113 at the first division of the typewheel 71 and the first impulse of any series moves the cam 109 ahead of armature 113, during the remainder 65 of the revolution and until the typewheel is returned to the first division, the armature 113 is free to drop back and close its contacts 112 when not attracted by magnet 114.

In this manner the second local circuit is held open at contacts 112 when no printing is being performed through the cam 109 and during the reception of impulses by magnet 114 but soon after the last impulse is over the arma- 70 75

ture 113 closes the second circuit through contacts 112 and the printing and restoring take place.

In the embodiment of our invention herein described, the proper operation of the magnets is thus largely dependent upon the speed at which they may be actuated or released, and in this connection it is well to note that the magnet 87 is fast in actuation and response to all impulses, while the magnet 88 is slow in actuation and quick in releasing and response only to the long impulses. The magnet 88 is in series with the slow relay magnet 114, whose armature may also be operated mechanically by cam 109, and is slow releasing when magnetically operated. Due to the mechanical construction of the armature 84 and the retarding effect of the slow relay magnet 114 in series with magnet 88, it responds only to prolonged impulses through magnet 88 and releases quickly when the current is cut off.

When no impulses are being received, the armature of relay 114 is held up by cam 109, and the first impulse disengages the cam and frees the armature, the armature still remaining in that position as long as the impulse, or series of impulses continues. All other magnets are made to operate or release as rapidly as is possible.

The sequence of operation of the several magnets is as follows; the closing of the line relay contact will send impulses through magnet 87 and slow relay 114 and magnet 88. If the impulses be short, magnet 87 will only operate and if long, magnet 87 and 88 will operate in the sequence. The slow relay will hold its contact open during the series of impulses. The operation of magnet 87 will only advance the typewheel one division for each impulse and the operation of magnets 88 and 87 together will advance the wheel one or more divisions per impulse. In any case that the operation of both magnets advances the wheel only one division the magnet 88 will shift the wheel along the shaft 72 to the second or third channel.

At the end of a series of impulses the slow relay will close its contact and operate the other magnets as follows: if the wheel is stopped on the first division the relay contact will close a circuit through magnets 89 and 104, magnet 89 allowing the wheel to complete its revolution to normal position and magnet 104 will shift the wheel to the first channel or normal position. Should the wheel be stopped on the second or any division from second to fifteenth, inclusive, the relay will close the printing magnet (300) circuit which in turn will close the circuit to magnets 89 and 104 restoring magnets 89 and 104 as on the first divisions. Should the wheel be stopped on the 16th division it will close a circuit through either the carriage return magnet 196 or stop magnet 342 depending upon the position of the typewheel with respect to its channel.

The restoring magnets are operated directly from the relay on the functional divisions, first division spacing and sixteenth division carriage return and stop. The relay operates the printing magnet which in turn operates the restoring magnets on the intermediate divisions.

In order that exact synchronism of speeds of the motors at the sending and receiving stations may not be required, in the practical operation of our improved system, we rotate the shaft 72 of the receiving mechanism at such a higher speed than we rotate the shaft 128 of the trans-

mitting mechanism so that even though the speeds of each of the motors at the sending and receiving stations vary within the commercial limits, at all times the speed of rotation at the receiving station will be in excess of that at the descending station, the pawl and escape wheel mechanisms herein described so operating that slippage of the clutch, Fig. 2, compensates for the difference in speeds in the effect produced upon the type wheel rotation. 10

Clearer understanding of the function of the escapement can be best seen by assuming that magnet 87 operates just ahead of magnet 88 on the longer impulses. All impulses whether long or short, through magnet 87 oscillate the fingers 15 18 and 79, once for every impulse allowing the escape wheel 75 and the typewheel 71 to advance one division for each impulse.

Should a long impulse be received the magnet 88 will shift finger 79 in line with escape-wheel 76 having a lesser number of teeth than the wheel 75. When a tooth on wheel 76 adjoins one on wheel 75, which is true for the first two teeth of wheels 75 and 76 the finger 79 will have been engaged even if shifted and the wheels will 25 be advanced but one division for each of the first two impulses. As the first two teeth are engaged by finger 79, both wheels 75 and 76 will be advanced but one division on the first two impulses of any series, whether the impulses be 30 long or short. Now should the third or following impulses be for a longer period, the finger 79 will be shifted to the wheel 76 by magnet 88 and the magnet 87 will lift finger 79 into engagement with wheel 76 whereby all the wheels 35 will be advanced until the finger 79 comes into contact with a following tooth which may be several divisions ahead.

It should be understood that at certain times an impulse slightly longer than that required to 40 advance the wheels one division will allow the wheels a free rotation for several divisions. With a short combination of impulses any one of several characters on the typewheel can be brought to the printing position. The first two impulses 45 of any series does not advance the wheel but one division each, any movement of the armature 84 on the first two impulses will cause the shifting of the typewheel to the second or third channel and the selection of a character in any channel 50 is accomplished thereby.

A view showing one combination of escape-wheel is best shown in Figure 10. The first vertical column represents wheel 76, the second wheel 75 and the third wheel 77. The horizontal divisions are the teeth on the respective wheels. It will be seen from this that finger 18 operates in column 2B when selecting and in column 3D when restoring the wheels to normal position, and finger 79 operates in column 2B on the short impulses, and in column 1C on the long impulses, 55 it is obvious that any character on the typewheel can be brought to the printing position with a certain combination of impulses and restored to its normal position by the operation of magnet 89. 60 65

After the selection of a character on the typewheel the printing takes place and then the wheel is restored to its normal position with respect to its further rotation to the first division and to its shifting to the first channel. The printing is 70 accomplished by magnet 300 (Figs. 5 and 9) which operate the swinging contact 415 on its pivot. Magnet 104 restores the typewheel to its first channel position and magnet 89 sets the escapement for the return of the typewheel to its first 75

division and operates contact group 416. The cam 107 actuates the contact group 110 on the first, second, and last divisions of the wheels and stops the operation of the printing hammer during this time these positions being used for other functions of the machine. Now as division 1 is the normal position of the typewheel and all circuits are open, one impulse either long or short, advances the wheels to the second division and 10 cam 109 will release armature 113. At the end of the impulse, armature 113 closes contacts 112 completing the typewheel restoring circuit from contact 112 through conductor 418, contacts 419 and 420, and conductor 421 where it is led into 15 magnets 104 and 89, thence through conductors 422, 423, and 424 to generator 407 and conductors 412 and 425 to armature 113.

Magnets 104 and 89 now return the wheel to normal channel and division respectively; the 20 rotating shaft 72, Fig. 1 operating the cam 107, Figs. 1 and 9; to cause engagement of contacts 427 and 428 which occurs immediately following the opening of contacts 431 and 432 by movement of the armature 83, thereby keeping the 25 printing magnet 300, controlled by contact 432, inoperative and spacing the paper carriage one division by means of the armature 83 Figs. 9 and 1 and the escapement 41, Fig. 1.

The transmitter cam adapted to close the line 30 for one impulse is connected to the space bar of the key board and spacing of the carriage occurs each time the space bar is depressed. When a character has been selected between the second and last division of the typewheel 71, cam 107 35 opens contacts between 419 and 420 and closes contacts between 427 and 428. The printing circuit has now been closed from contact 112, through conductor 430, contacts 431 and 432, conductors 434 and 435, printing magnet 300, conductor 436, contacts 427 and 428, conductor 437, generator 407, conductors 412 and 425 to armature 113.

This energizes the printing magnet 300 which operates the printing hammer 297, closing contacts 415 and completing the restoring circuit from contact 112, through conductors 430 and 438 to contact 415, conductors 439 and 421 to magnets 89 and 104, through conductors 422, 423, and 424 to generator 407, conductors 412 and 425 50 to armature 113. Magnet 104 shifts the typewheel to the first channel and magnet 89 allows the typewheel to rotate to the first division opening the printing circuit at contacts 431 and 432. Simultaneously contacts 431 and 433 are closed, 55 short circuiting contact 415 so that magnets 104 and 89 remain energized after the printing magnet is cut out, and until the restoring operation is complete.

The foregoing describes all operations, except 60 those for the last division 16 of the typewheel, which division is utilized for the carriage returning, and the motor stopping functions. The carriage returning and stop functions are controlled by cam 108 Figs. 1 and 9 which closes contacts 65 111 at the last-division position of the typewheel, contacts 440 which are operated by the typewheel lever arm 93 and contacts 431 and 432 operated by the armature 83. The non-printing position of the typewheel is maintained by cam 70 107 and contacts 110.

A carriage return and a stop key is provided on the transmitter and when the stop key is depressed, the impulses sent out will bring the typewheel 71 around to the last division in the first 75 channel and the carriage return key brings the

wheel to the last division but in the second channel. Pressing the stop key brings the wheel to a position where cam 108 closes contacts 111 and arm 93 holds contacts 441 and 442 closed. Upon completion of a series of impulses, armature 113 closes the circuit from contacts 112 through conductor 430 to contacts 431 and 432 to conductor 444, contacts 111, contacts 441 and 442, magnet 342, conductors 445 and 424, generator 407, conductors 412 and 425 to armature arm 113. 10

The above circuit described causes magnet 342 to operate armature 340 and the motor switch, at the same time the restoring circuit is closed through contact 112, conductor 418, contacts 419 and 420, conductors 421, 446, and 441, magnets 15 104 and 89, conductors 422, 423, and 424, generator 407, conductors 412 and 425 to armature 113.

Armature 83 opens contacts 431 and 432 cutting off the magnet 342 allowing the typewheel 20 11 to restore to its normal position and advancing the paper carriage one division. The operation of the carriage return key will also bring the typewheel to the last division and in the second channel so that the wheel shifts to the second channel and armature arm 93 opens the contacts 441 and 442 closing contacts 442 and 443. The armature 113 is now released and a circuit will be established as just described, except from conductor 448 to contacts 442 and 443 through conductor 449, carriage return magnet 196 (Figs. 6 25 and 9) and conductor 451 to conductor 424. 30

Carriage return magnet 196 is now energized 35 and attracts its armature 193 which engages the carriage return clutch. As heretofore stated, when the carriage 151 reaches the extreme limit of movement in the spacing direction, it automatically trips the carriage return clutch through a suitable mechanical means, or it can be accomplished through contact 202. When a circuit is completed between contact 454 and conductor 449, as shown by the dotted line 455 (Fig. 9), each time the carriage rack 200 closes contact 202 a circuit will be established through carriage return magnet 196 from one side of 45 generator 407 through conductors 412 and 456, contacts 452, 453 and 454, conductors 455 and 449, carriage return magnet 196, conductors 451 and 424 to the opposite side of the generator 407. 40

The carriage return clutch, after being operated by momentarily closing contact 202 as required, remains engaged until the carriage reaches the end of its travel where the clutch is released. A signal is provided to indicate when the end of the printing space is near at 55 hand. Preferably lamp 457 as the indicator is used, the current being supplied by the generator 407 through contacts 452 and 453. These contacts can be so adjusted that the rack 200 on the paper carriage will close them preferably five or six spaces from the end of the carriage travel so that the lamp will light notifying the operator of the approach of the carriage near the end of its travel. It will be seen that because of the lamp signal, splitting of words through the functioning of the carriage return arrangement will be avoided. The same sequence of operation occurs for all characters printed and every mechanical function of the machine. 60 65 70

Escapewheel and typewheel chart

The chart of the peripheries of the escape wheels and the typewheel is shown in a single plane in Fig. 10. The relation of the teeth on 75

the three wheels 76, 75, and 77, and their relation to the character and functional points on the typewheel are best shown in that figure.

The vertical columns 76, 75 and 77 are schematic views of the escapewheels best shown in Fig. 1, and the horizontal columns are the teeth on the wheels. Vertical columns 1, 2 and 3 are a similar view of the three circumferentially disposed channels of the typewheel, the horizontal columns are the character and functional points on the wheel. The chart shows a 17 division, 3 channel typewheel having 47 printing and functioning positions.

The direction of rotation is shown by the arrow, the normal division 460 is at the bottom of the Figure 10. The escapefinger 78 (Fig. 1) rests at division 460 in column 75. Inasmuch as the fingers 78 and 79 operate as a unit on escapewheel 75, the position of these fingers can be traced in column 75 of the chart, one division for each short impulse in any series. If finger 78 actuates escapewheel 75, and finger 79 actuates escapewheel 76, the position of the fingers can then be traced in column 76. When finger 78 is engaging escapewheel 77, the finger movement can be followed to the single tooth in column 77 in the normal starting division 460.

Assuming that the finger 78 moves up to the following tooth in the column 75, for each short impulse, and up one tooth in column 76 for each long impulse imparted thereto, it is obvious how any particular division can be reached with a combination of long and short impulses, in less time than that required with a long series of short impulses.

Referring now to vertical columns 1, 2 and 3 of Fig. 10, which as stated heretofore, are the three rows of characters around the periphery of the typewheel (called channels), and the three horizontal positions (called a division), it will be seen that each division of the escapewheels coincides with three position on the typewheel. The selection of a division on the escapewheels has reference to any one of the three horizontally disposed points on the typewheel, and the horizontal, or channel selection is gained through the first two impulses of any series. If the first, and second impulses be short, the typewheel will remain fixed in the first channel, and can be traced up the vertical column 1, and if the first impulse is a short one and the second a long impulse, the wheel will shift to the second channel, which can be traced in vertical column 2. However, if the first two impulses are long ones, the wheel will be shifted to the third channel and should be traced in vertical column 3.

For example, suppose that the point 465 on the typewheel chart is a desired character. It is in the second channel and tenth division of the wheel. The transmitter code for that character could be, one short, two long and two short impulses (— — —). Tracing this by the light line in columns 75 and 76 the first short impulse would reach the second division in column 75, the second being a long impulse would move to the third division and the third being a long impulse would move to 461 in column 76 while the short fourth and fifth impulses would move in divisions 462 and 463 in column 75.

This co-operation of units would then bring the typewheel around from the division 460 to division 463 which is occupied by three printing characters. As the typewheel is shifted one

channel as in this case, for each long impulse of the first two of any series, the typewheel would be shifted to the second channel by the long second impulse. The point 465 would be reached as indicated in columns 1 and 2. 5

Should the first impulses in this series be short division 463 in the first column would have been reached and, likewise division 463 in the third column would have been reached had the series started with two long impulses. With 10 wheels constructed as shown, any one of 47 points referred to on the typewheel can be reached with a combination of six impulses.

In the restoring operation the finger 78 when shifted to escapewheel 77 will be engaged by the tooth in that wheel which is division 1, and the typewheel will have been returned to starting position. The typewheel makes one complete revolution for each printing, or other function and is stopped at the point selected just long enough 20 for such function to occur. The printing and operating functions can be distributed over the typewheel to suit any particular requirements by arranging the cam code wheel and the keys of the transmitter accordingly. It should be 25 noted that more than one impulse code can be used for the selection of any operating point on the typewheel, except the one in the division 464, channel 77, which is a blank and cannot be reached by any combination. 30

Referring now to Fig. 2 of the drawings we have illustrated a fragmentary view of one type of clutch which may be employed to drive the shaft 72 from the source of power. The clutch comprises a cylindrical sleeve 82 keyed in any 35 suitable manner to one end of the shaft 72 and is adapted to internally receive a driven drum 510. The drum 510 is keyed or fastened in any suitable manner to the driving shaft 92, at 522, and is on the same axis of rotation as the sleeve 40 82. It will be seen that the shafts 72 and 92 can be frictionally connected.

Loosely carried by the drum 510 are preferably a pair of friction shoes 511 and 512. The shoes are composed of a cylindrical metallic shell 45 adapted to receive and retain felt, or the like, faces 513 and 525 in extended position beyond the metallic shell portion of the shoe. These shoes are retained in frictional engagement with the internal periphery of the sleeve 82 by the 50 force exerted on them by the springs 514 and 515 disposed in any convenient manner on the shaft 92 and extending inwardly to engage the inner side of the friction shoes 511 and 512 and force them outwardly into frictional engagement 55 with the cylindrical sleeve 82 thereby connecting the drive shaft 92 with the driven shaft 72.

The springs 514 and 515 are capable of having the tension applied to the shoes 511 and 512 adjusted preferably through the agency of a 60 wedge member 517 disposed on the drive shaft 92 in any suitable manner. It will be seen that by shifting the wedge member 517 to the right forcing the inturned ends of the springs outwardly accordingly increasing the outward pressure of the spring arms 514 and 515 on the friction shoes 511 and 512. Therefore by shifting the wedge member 517 to the left the tension of the springs 514 and 515 is decreased and the frictional engagement between the shoes 511 and 70 512 with the sleeve 82 is proportionately decreased. 65

Referring now to Fig. 4, of the drawings, the action of the cam wheels 127 on the drive shaft 128 can be more clearly understood by reading 75

the description of this figure with Fig. 3. The cam 127 and the slotted disk 126 are suitably combined on a sleeve as a unit and rotatably disposed on shaft 128. Disposed adjacent to each unit is a ratchet wheel 124 and on the same vertical plane with pawl 125. The pawl 125 is pivotally mounted on disk 126 and is engaged with the ratchet wheel 124 when the pawl 125 is released by the action of the escape fingers 122 10 and 123, intermittently rotating the cam unit as hereinbefore more fully described. It follows that rotation of the cam 127 transmits a vertical oscillation to contact fingers 129 through the rollers journaled in the fingers 129 adapted to 15 ride upon the periphery of the cam wheel 127.

Referring particularly to Figs. 5a and 6a of the drawings, it will be noted that I have provided a structure whereby the printing mechanism may be elevated above and overhang the 20 paper and paper carriage to make possible clear vision of the printed matter upon a movable supply of paper.

It will be noted also that the paper roll 152, 25 the guiding rollers 156, 157, and guides 160 are so related to the direction of winding of the paper on the roll 152 and position of the type wheel 71 that the paper 33 as it emerges past the type wheel will, by virtue of the natural "curl" imparted to the paper by winding it upon the roll 152, effect a tilting or deflection of the paper over the top of the type wheel 71, and prevent the end of the paper again being received within the rolls or struck by the printing hammer and will feed out to a suitable receptacle or intermediate cutting mechanism not shown.

Having thus described our invention as embodied in a particular electromagnetic system and as particularly applied to printing telegraph 40 mechanisms and systems, we are aware that numerous and extensive departures may be made from the embodiment herein illustrated and described and we appreciate that our invention may be advantageously employed in electromagnetic 45 mechanisms other than printing telegraph systems and mechanisms and we particularly contemplate the employment of the selective mechanism of this invention wherever it is desired to move a selector element in a step by step manner and particularly where the same is movable in two dimensions.

Subject matter illustrated and described but not claimed herein may be claimed in divisional application, Serial No. 43,338 filed January 31, 1935 for improvements in Telegraph typewriters and apparatus.

We claim:

1. In a typewriter mechanism, a type wheel, a ribbon, a printing hammer, a ribbon elevator, 60 means to elevate the elevator and a stop for the elevator, said hammer being pivotally associated with the elevator and communicating shifting movement thereto and adapted responsive to stoppage thereof, by inertia effect, to be swung 65 upon its pivot to effect a printing operation co-operatively with said ribbon and type wheel.

2. In a typewriter mechanism, a type wheel, a ribbon, a printing hammer, a ribbon elevator, 70 means to elevate the elevator and a stop for the elevator, said hammer being pivotally associated with the elevator and communicating shifting movement thereto and adapted responsive to stoppage thereof, by inertia effect, to be swung 75 upon its pivot to effect a printing operation co-operatively with said ribbon and type wheel,

and an electromagnet for operating said elevator and hammer.

3. In a typewriter mechanism, a laterally movable paper carriage, a roll of paper carried at the front of the carriage, means to direct paper from the roll in a depending loop from the rear face thereof, downwards and upwards beyond the printing position, a printing hammer, a lever having an end projecting within the loop of paper, said hammer pivoted to said lever end, 10 and means responsive to movement of said lever to elevate the hammer to effect a printing operation, and stop means engaging an arm of said hammer and upon a predetermined movement of the lever effecting a rotation of the hammer upon its pivots to effect a printing operation upon the paper in printing position.

4. In a typewriter, a stationary frame therefor, printing mechanism supported by the frame, a reciprocable roll of paper supply, a paper 20 carriage, said carriage entirely supporting said roll, said printing mechanism mounted solely on said frame, and elevated above and overhanging the paper roll and paper carriage, and comprising a paper striking element pivoted at a 25 point above the paper.

5. In a typewriter mechanism, a type wheel, a printing ribbon, a ribbon elevator, an elevator stop, a movable power supplying element, a striking element movable to effect a printing operation in cooperation with the ribbon and wheel, 30 a movement transmitting element movable bodily to transmit movement of the power supplying element to the elevator to raise it to engage the stop and pivotally movable about a fulcrum on 35 the stopped elevator to transmit movement of the power supplying element to the striking element to move it.

6. In a typewriter mechanism, a type wheel, a printing ribbon, a ribbon elevator, an elevator 40 stop a movable power supplying element, a striking element movable to effect a printing operation in cooperation with the ribbon and wheel, a transmitting element pivotally supported on the power supplying element movable bodily there- 45 with to transmit movement thereof to the elevator to raise it to engage the stop and pivotally movable on the power supplying element and about a fulcrum on the stopped elevator to transmit movement of the power supplying ele- 50 ment to the striking element to move it.

7. In a typewriter mechanism, a laterally movable paper carriage, a roll of paper carried on the carriage, means to direct paper from the roll in a depending loop downwardly and upwardly 55 beyond the printing position, a printing hammer, an element having a portion disposed within the loop of paper, the hammer being pivoted to the said element, and means responsive to movement of said element to elevate the hammer to 60 effect a printing operation, and stop means engaging a portion of said hammer and upon a predetermined movement of the element effecting a rotation of the hammer upon its pivot to effect a printing operation upon the paper in 65 printing position.

8. In a typewriter mechanism, a type wheel, a printing ribbon, a ribbon elevator, a stop for the elevator, a movable power supplying element, a striking element movable to effect a printing 70 operation in cooperation with the ribbon and wheel, a movement transmitting element for transmitting movement from the power supplying element to the elevator to raise it to a printing position as determined by the stop, the 75

transmitting element also transmitting movement from the power supplying element to the striking element to move it to cause the striking element to strike the ribbon subsequent to the 5 elevator engaging the stop.

9. In a typewriter mechanism, a type wheel, a printing ribbon, a ribbon elevator, a stop for the elevator, a movable power supplying element, a striking element movable to effect a printing 10 operation in cooperation with the ribbon and wheel, a movement transmitting, pivotally supported element for transmitting movement from the power supplying element to the elevator to raise it to a printing position as determined by the stop and the pivoted element also transmitting movement from the power supplying element to the striking element to cause the striking element to strike the ribbon subsequent to engagement of the elevator with the stop.

10 10. In a typewriter mechanism, a type wheel, a printing ribbon, a ribbon elevator, a stop for the elevator, a movable power supplying element, a striking element movable to effect a printing 15 operation in cooperation with the ribbon and wheel, a transmitting element pivotally supported on the power supplying element movable 20 bodily therewith to transmit movement thereof to the elevator to raise it to a printing position as determined by the stop, and the transmitting element being pivotally movable on the power supplying element to transmit movement thereof to the striking element to effect striking the ribbon subsequent to the elevator engaging the stop.

bodily to transmit movement of the power supplying element to the elevator to raise it to a printing position as determined by the stop, and the pivotal element being movable pivotally to transmit movement of the power supplying element to the striking element to cause the striking element to strike the ribbon in printing position. 5

11. In a typewriter mechanism, a type wheel, a printing ribbon, a ribbon elevator, a stop for the elevator, a movable power supplying element, a striking element movable to effect a printing 10 operation in cooperation with the ribbon and wheel, a transmitting element pivotally supported on the power supplying element movable 15 bodily therewith to transmit movement thereof to the elevator to raise it to a printing position as determined by the stop, and the transmitting element being pivotally movable on the power supplying element to transmit movement thereof to the striking element to effect striking the ribbon 20 subsequent to the elevator engaging the stop.
